UNITED STATES PATENT OFFICE.

JAMES PRICE AND ALVAH W. BROWN, OF GRAND RAPIDS, MICHIGAN.

BURNER.

1,177,801.

Specification of Letters Patent.

Patented Apr. 4, 1916.

Application filed December 16, 1915. Serial No. 67,241.

To all whom it may concern:

Be it known that we, JAMES PRICE and ALVAH W. BROWN, citizens of the United States of America, residing at Grand Rapids, in the county of Kent and State of Michigan, have invented certain new and useful Improvements in Burners; and we do hereby declare the following to be a full, clear, and exact description of the invention, such as will enable others skilled in the art to which it appertains to make and use the same.

This invention relates to burners and while of especial value when used in connection with fumigating apparatus, it is of course understood that the burner may be used in many other relations.

It is the object and purpose of our invention to provide a burner in which a solid fuel such as paraffin or the like may be used and in which, by virtue of the novel construction of the burner, a complete combustion of the fuel may be had, the flame produced being of a bluish character without the presence of color indicating the presence of particles of carbon and incomplete combustion thereof.

A further object of the invention consists in the provision of a construction with readily separable parts for the introduction of fuel into the burner and of a receptacle to be used in connection with the burner which is easily detached therefrom or which may be replaced by a similar receptacle containing material to be vaporized by the burner.

Various other objects and purposes other than those specifically enumerated will also appear as understanding is had of the construction which embodies our invention disclosed in the accompanying drawing, in which;

Figure 1 is a side elevation of the burner with all parts assembled and in place. Fig. 2 is a vertical section taken through the construction shown in Fig. 1; and Figs. 3 and 4 are sections taken on the lines 3—3 and 4—4, respectively, of Fig. 2.

Like reference characters refer to like parts throughout the several views of the drawing.

In the construction of the burner a shell-

like casing 1 made of thin sheet metal and in the form of a cylinder open at each end is used which at its middle portion is provided with a plurality of rows of openings 2, 55 which openings lie between the lower part of the receptacle which is placed in the upper end of the shell and above a member 3 fixed inside this shell by soldering or other suitable connection and below which the fuel is 60 located. Member 3 is in the shape of a shallow inverted cup and at its central point has a portion cut away to form a circular opening 4. At a short distance from the edges of opening 4 a plurality of small 65 openings 5 are formed and immediately below the lower edges of member 3 a row of openings 6 are made in the shell 1. The shell thus described is adapted to be detachably connected with a fuel holding 70 standard comprised of a plate 7 of sheet metal from which project downwardly extending legs 8, four in number being indicated in the present construction. Each leg is formed with a bead 9 against which 75 the lower edges of the shell 1 engage so that the shell passes over the upper part of the standard and is stopped by the beads in such position that the row of openings 6 is directly above the plate 7. The central portion of the plate is removed and in the opening formed a shallow cup 10 is 80 fixed which is adapted to receive the fuel. In the operation of the burner a wick 11 of conical form is used which is adapted to 85 be forced over a sheet metal member 12 having its ends bent angularly as indicated at 13 so that it will stand upright and hold the wick in proper position directly below the opening 4 in the member 3. 90

A receptacle 14 formed of sheet metal is detachably positioned in the upper end of the shell 1 being formed with a bead 15 which limits the distance that the receptacle 14 may be inserted in the shell, the bottom 95 of this receptacle coming immediately above the upper row of openings 2 in the shell. Adjacent its upper end receptacle 14 is made smaller in diameter and terminates in a screw threaded neck 16 to which a screw 100 threaded cap 17 may be secured.

It is apparent of course that various types

of receptacles may be used with this burner but a receptacle of the form described has been found most efficient when the device is used for fumigating purposes, the fumigating material being contained by the receptacle and the cap being removed when a room is to be fumigated.

When the parts of the burner are assembled and with fuel in the cup 10 which, 10 preferably, is of paraffin, the wick may be lighted and for a short time a yellowish flame will be produced but after the device has become warmed air passing through the openings 6 to the wick and 15 through the openings 5 to a point above the member 3 will furnish sufficient oxygen that particles of carbon in the flame not completely burned adjacent the wick but carried by the flame above the member 3, will 20 combine with the oxygen of the air passing through the openings 5 and a complete combustion without trace of smoke will be had. The flame extends to the bottom of the receptacle and spreads outwardly over the 25 entire bottom but will not pass through the small openings at 2 in accordance with the well known principle, examples of which are found in miners' lamps and the like. However, the plurality of openings 2 will 30 also permit the entrance of air from the outside so that, this air will aid in the combustion of the fuel.

With a burner of this character it has been found that a definite quantity of fumigating material may be vaporized in the receptacle 1 in a time practically one-third of that heretofore required to vaporize the same amount of material with other burners now on the market and this without danger 40 of fire from the burner.

We claim:—

1. In combination, a cylindrical shell open at both ends and provided with a plurality of rows of openings situated at a distance 45 from the ends of the shell and with a single row of openings located a distance from said plurality of rows, an inverted cup-like member having a large central opening and a plurality of small openings adjacent and surrounding said large opening secured in the shell between the single row and the plurality of rows of openings, a receptacle positioned in one end of the shell and detachable therefrom, the bottom of said receptacle lying in 55 a plane substantially coincident with an upper row of the plurality of rows of openings, a fuel holding standard detachably positioned in the opposite end of the shell having its upper surface in a plane slightly below that of the single row of openings, legs 60 to said standard, beads on the legs limiting the insertion of the standard into the shell, and a cup for containing fuel secured centrally on the standard.

65 2. In combination, a shell open at both

ends and provided with a plurality of openings at a distance from the ends of the shell, and with a single row of openings located between said plurality of openings and the lower end of the shell, a member secured within and extending across the shell, said member being provided with a comparatively large central opening and with a plurality of smaller openings adjacent and around the larger opening, said member lying between the single row of openings and the plurality of openings in the shell, a receptacle removably inserted in the upper end of the shell, a fuel holding device removably inserted in the lower end of said shell, and means to limit the insertion of said receptacle and device into the shell. 70

3. In combination, a shell having a member secured within and across it at a distance above the lower end of the shell, said shell having a plurality of openings in the sides thereof above said member and a single row of openings below it and said member having a comparatively large opening in the center thereof with a plurality of smaller openings around and adjacent said large opening, a receptacle removably inserted in the upper end of the shell and a fuel holding member removably inserted in the lower end of the shell adapted to contain a wick located below the larger central opening in said member. 75

4. In combination, a shell, a member secured within and across the shell between the ends thereof, said shell being provided with openings in its sides above and below the member to permit the entrance of air, and said member having a large central opening with auxiliary smaller openings adjacent the large opening, a receptacle inserted in the upper end of the shell, a bead on the receptacle to limit the inward movement of said receptacle, a fuel holder having a plurality of depending legs inserted in the lower end of the shell and beads on said legs to stop the inward movement of said fuel holder into the shell. 100

5. In combination, a shell having a member secured within and across it a distance above the lower end thereof, said shell being provided with openings in its sides above and below the member to permit the entrance of air, and said member having a central opening, a receptacle removably inserted in the upper end of the shell, a fuel holding member removably inserted in the lower end of the shell and a wick located in the fuel of said fuel holding member below the plane of the first mentioned member whereby the flame from the wick passes through said central opening. 115

6. In combination, a shell having a member secured within and across it at a distance above the lower end thereof, said shell being provided with openings in its sides above 120

and below the member to permit the entrance of air, and said member having a plurality of openings at and adjacent the center thereof, a fuel holding member at the lower end 5 of the shell and a wick located below said first mentioned member, substantially as described.

In testimony whereof we affix our signatures in presence of two witnesses.
